UNITED STATES PATENT OFFICE.

WEBB JAY, OF CHICAGO, ILLINOIS.

LIQUID-ELEVATING DEVICE FOR AUTOMOBILE-ENGINES.

1,132,941.

Specification of Letters Patent. Patented Mar. 23, 1915.

Application filed June 26, 1914. Serial No. 847,418.

To all whom it may concern:

Be it known that I, WEBB JAY, a citizen of the United States, residing at Chicago, in the county of Cook and State of Illinois, have invented new and useful Improvements in Liquid-Elevating Devices for Automobile-Engines, of which the following is a specification, reference being had to the accompanying drawings, forming a part thereof.

10 The purpose of this invention is to provide a convenient and easily accommodated means for elevating the liquid fuel or other liquid supply for an internal combustion engine of an automobile from a storage tank in the usual low position, to a position from which it may be fed by gravity to the carburetor or other part requiring it.

It consists in the elements and features of construction shown and described as indicated in the claims.

In the drawings:—Figure 1 is a side elevation of a structure embodying this invention, shown in association with an automobile engine or parts thereof. Fig. 2 is a section at the line, 2—2, on Fig. 1. Fig. 3 is a partly sectional elevation of the supplemental liquid fuel receptacle, section being made in a vertical plane cutting the various connections.

30 In the structure shown in the drawings, 1 represents a receptacle for liquid fuel, located at a position from which the fuel may be fed by gravity to a carburetor, indicated in dotted lines at 2.

35 3 is a pumping device which, as illustrated, comprises a piston, 4, playing in a cylinder, 5, the cylinder being open at one end and the piston being connected at that end for its operation by means of the arm, 9, of an eccentric strap, 10, of an eccentric, 11, mounted upon a rotating shaft, 12, which may be the cam shaft of an engine or a counter-shaft driven by any convenient connection with any rotating shaft of the engine structure, or associated mechanisms, in substantially continuous operation. The pump chamber is connected to a second pipe line, 13, containing two check valves, 14 and 15, which both open for flow in the same direction through the pipe line, and are adapted to be closed by flow in the opposite direction.

40 As illustrated, the two valves are both mounted in the head, 16, of the cylinder. This, however, is merely a matter of convenience in construction. It will be observed that as to function, the pump is located between the

two check valves. The pipe line, 13, leads from the upper part of the receptacle, 1, and the valves open for flow away from said receptacle. A pipe line, 18, leads from the lower part of a low level storage tank, 17, and discharges into the elevated receptacle, 1. Said receptacle, 1, is closed at the top so that a partial vacuum may be produced above the liquid therein. At each rotation 65 of the shaft, 12, the withdrawing stroke of the piston produces a partial vacuum tending to draw air from the receptacle, 1, past the check valve, 15, producing a partial vacuum in said receptacle, 1, above the liquid 70 level therein, and the opposite stroke of the piston forces the air out past the check valve, 14. The result of continuous operation is therefore to produce a sufficient partial 75 vacuum in the receptacle, 1, above the liquid level therein, to cause the fuel to be lifted by atmospheric pressure from the low level tank, 17, through the pipe, 18, to the receptacle, 1, to keep the same supplied for feeding by gravity to the carburetor, or wherever else the oil is required for the engine.

In the absence of means to prevent it, it will be evident that the receptacle, 1, might be over-filled by continuous operation of the diaphragm pumping device, in which 85 case the liquid elevated into that receptacle would flow back into the pump chamber and out through the check valve, 14. To prevent such over-flowing or over-filling of the receptacle, 1, provision is made for interrupting the partial vacuum by means of which the oil is lifted into said receptacle when a pre-determined high level of liquid is attained therein. This means consists in providing a vent pipe, 20, which terminates 90 in an air-inlet, 21, at a position conveniently near to the upper end of the receptacle, 1, said vent pipe leading in any manner to the pump chamber, which is most conveniently accomplished by making it a 95 branch of the pipe line, 13, from the receptacle to the check valve, 15. A valve, 22, normally closes the air inlet, 21, but is operated for opening against the suction by connection with a rock shaft, 23, journaled in 100 the receptacle, 1, and protruding therefrom to carry a lever arm, 24, upon which the valve, 22, is mounted. Inside the receptacle, 1, a float, 25, is carried on a lever arm, 26, extending from the same rock shaft, and 110 which when not upheld by the liquid in the receptacle, operates in addition to the suc-

tion as a weight to hold the valve, 22, seated, but when lifted by the rise of the liquid to a predetermined high level in the receptacle, rocks the shaft and opens the valve, 22. 5 The same expedient, namely, relieving the partial vacuum at intervals, and whenever a pre-determined high level of liquid is obtained, is necessary in order to permit the liquid lifted by the partial vacuum into the 10 receptacle, 1, to flow out by gravity to the parts to be supplied. An adequate difference between the high liquid level at which the valve, 22, is opened by the float, and the low level at which it is closed by the float 15 operating as a weight, is obtained by making the area of the port closed by the valve large enough to cause the suction to hold the valve seated until the float is submerged as much beyond the normal depth as the 20 desired difference between the high and low levels, so that when the upward pressure on the float is enough to pull the valve from its seat, the float will rise and carry up the valve a distance which will measure the 25 amount which the liquid level must fall before the valve again seats; and when this happens, the suction operating at the next stroke of the pump device holds it seated.

When this device is used for supplying 30 oil to the carburetor, the receptacle, 1, is connected with the float chamber, 27, which is suitably connected with the receptacle, 1, and with the atmosphere for maintaining a liquid level in the carburetor adapted to the 35 needs of the latter but which forms no part of this invention and need not be further described.

The means herein shown for lifting from 40 the low level tank to a high level receptacle may obviously be employed for so handling any liquid required by the engine, as, for example, the lubricating oil; and I do not limit myself to the use of these devices for supplying the carburetor with fuel oil, 45 though some of the specific features are especially applicable to that use and are specifically claimed for such use. Also it will be obvious that the described action of the pumping device is not dependent upon 50 the back-and-forth moving member being a piston, though a piston pump is preferred to other equally well known forms of pump when the space available is adapted to accommodate a proper stroke of the piston.

55 I claim:

1. In combination with an engine requiring oil, a main oil supply tank at a low level; a receptacle located at a level from which the oil required by the engine may 60 be supplied thereto by gravity; a pipe line connecting the main supply tank with the elevated receptacle, said receptacle being normally closed so that a partial vacuum may be produced therein; a second pipe line 65 leading from the upper part of the recep-

tacle; a suction pump device having its chamber intake communicating with said second pipe line; said second pipe line having an air inlet in addition to its communication with the receptacle; a normally closed valve for controlling entrance of air through said additional air inlet; a float in the receptacle adapted to be operated by the liquid contents thereof, and connections from said float for opening said last-mentioned valve 75 at a predetermined high level of the liquid in the receptacle.

2. In combination with an engine requiring oil, a main oil supply tank at a low level; a receptacle located at a level from 80 which the oil required by the engine may be supplied thereto by gravity; a pipe line connecting the main supply tank with the elevated receptacle, said receptacle being normally closed so that a partial vacuum 85 may be produced therein; a second pipe line leading from the upper part of the receptacle; two check valves in said second pipe line opening for flow away from the receptacle and adapted to be closed by flow 90 in the opposite direction; a pump chamber connected with the second pipe line intermediate the check valves, a back-and-forth moving member closing said chamber at one side; exteriorly-connected engine-operated 95 means for operating said member, said second pipe line having an air inlet in addition to its connection with the receptacle; a normally closed valve for controlling entrance of air through said additional inlet; 100 a float in the receptacle adapted to be operated by the liquid contents thereof, and connections from said float for opening said last-mentioned valve at a predetermined high level of the liquid in the receptacle. 105

3. In combination with an engine requiring oil, a main oil supply tank at a low level, a receptacle located at a level from which the oil required by the engine may be supplied thereto by gravity; a pipe line connecting the main supply tank with the elevated receptacle, said receptacle being normally closed so that a partial vacuum may be produced therein; a pipe line leading from the upper part of the receptacle; two 110 check valves in said pipe line opening for flow away from the receptacle and adapted to be closed by flow in the opposite direction; a pump chamber connected with the pipe line intermediate the check valves; a 115 back-and-forth moving member closing said chamber at one side; exteriorly-connected engine-operated means for operating said member, said pipe line having an air inlet in addition to its communication with the 120 receptacle; a normally closed valve for controlling entrance of air through said additional inlet, positioned and adapted for being held on its seat by suction at said inlet; a device buoyed by the liquid in the recep- 125 130

tacle, and connections therefrom for forcing said valve off its seat against the suction upon a predetermined submergence of said device.

5 4. In combination with an engine requiring oil, a main oil supply tank at a low level, a receptacle located at a level from which the oil required by the engine may be supplied thereto by gravity; a pipe line connecting the main supply tank with the elevated receptacle, said receptacle being normally closed so that a partial vacuum may be produced therein; a second pipe line leading from the upper part of the receptacle; two 10 check valves in said second pipe line opening for flow away from the receptacle and adapted to be closed by flow in the opposite direction; a pump chamber connected with said second pipe line intermediate the 15 check valves; a back-and-forth moving member closing said chamber at one side; exteriorly-connected engine-operated means for operating said member, said second pipe line having an air inlet and a valve for controlling entrance thereto positioned in the vicinity of the elevated receptacle and adapted to be held on its seat by the suction through said inlet; a device buoyed by the liquid in the receptacle, and connections 20 therefrom for forcing said valve off its seat against the suction upon a predetermined submergence of said device.

5. In combination with an engine requiring oil, a main oil supply tank at a low

level, a receptacle located at a level from 35 which the oil required by the engine may be supplied thereto by gravity; a pipe line connecting the main supply tank with the elevated receptacle, said receptacle being normally closed so that a partial vacuum 40 may be produced therein; a second pipe line leading from the upper part of the receptacle; two check valves in said second pipe line opening for flow away from the receptacle and adapted to be closed by flow in 45 the opposite direction; a pump chamber connected with the second pipe line intermediate the check valves; a back-and-forth moving member closing said chamber at one side; exteriorly-connected engine-operated 50 means for operating said member, said second pipe line having a branch which has an air inlet; a valve positioned in the vicinity of said receptacle adapted to be seated by suction for controlling said air inlet; 55 a device buoyed by the liquid in the receptacle, and connections therefrom for forcing said valve off its seat against the suction upon a predetermined submergence of 60 said device.

In testimony whereof, I have hereunto set my hand, at Chicago, Illinois, this 24th day of June, 1914.

WEBB JAY.
